INVENTOR
HERBERT C. MOORE
BY

Heard Smith & Fennant.

ATTYS.

UNITED STATES PATENT OFFICE.

HERBERT C. MOORE, OF SOMERVILLE, MASSACHUSETTS, ASSIGNOR OF ONE-HALF TO
BOSTON FLOOR COMPANY LIMITED, A CORPORATION OF MASSACHUSETTS.

PORTIÈRE OR CURTAIN HANGER.

1,152,383.

Specification of Letters Patent. Patented Aug. 31, 1915.

Application filed December 19, 1914. Serial No. 878,191.

To all whom it may concern:

Be it known that I, HERBERT C. MOORE, a citizen of the United States, and resident of Somerville, county of Middlesex, State 5 of Massachusetts, have invented an Improvement in Portière or Curtain Hangers, of which the following description, in connection with the accompanying drawing, is a specification, like characters on the drawing 10 representing like parts.

This invention relates to improvements in hangers for portières and like articles which are supported at a plurality of points upon 15 slidable members so that the portière may be extended or collapsed as may be desired.

The object of the invention is to provide a simple and cheaply constructed device which will be easy and certain in operation and will possess sufficient strength to hold heavy 20 portières and still be sufficiently inconspicuous to support light curtains as well.

Other objects will more fully appear from the following description and will be pointed out in the annexed claims.

25 In the drawings: Figure 1 represents a doorway or window with portière or curtain hanger embodying my invention attached thereto. Fig. 2 is a detail side elevation of a guideway provided with a longitudinally 30 extending recess in which is mounted a runner constructed in accordance with one form of my invention. Fig. 3 is a vertical transverse sectional view of a molding designed to support the runners of a portière hanger 35 and showing in elevation one of the runners mounted therein. Fig. 4 is a detail elevation of one of the preferred forms of runner. Fig. 5 is a vertical transverse sectional view of a different form of molding having a 40 rectangular longitudinally extending aperture with runners of the character illustrated in Fig. 3, mounted therein. Fig. 6 is a detail side elevation of a portion of one of the molding members with a different form of 45 runner mounted therein, and, Fig. 7 is a vertical transverse sectional view of a molding supporting the form of runner illustrated in Fig. 6.

50 Portière hangers of the class illustrated herein comprise a longitudinally extending runway in which is mounted a series of runners having depending members adapted to receive the hooks of the pins which support the curtains or portières.

55 Fig. 1 illustrates a portion of a doorway

having side posts 1—2 and a lintel 3, a molding 4, provided with a longitudinally extending aperture or runway 5 being secured to the underside or the front face of the lintel 3, and a series of suitable runners 6, 60 such as illustrated in Figs. 2 and 4, being slidably mounted in the longitudinal aperture 5. Any desired form of molding may be used. It will also be understood that if the device is to be used as a curtain hanger 65 the molding may be attached to the top of the window frame in any suitable manner. The molding is desirably formed in two sections 7, 8, (see Figs. 3 and 5) which may be glued or otherwise secured together in 70 any suitable manner. Each of the strips of molding is provided with longitudinally extending grooves so disposed that when the sections 7, 8 are placed adjacent each other as illustrated in Figs. 3 and 5 the longitudinal 75 grooves will form a cylindrical or rectangular aperture or runway extending the entire or substantially the entire length of the molding.

The lower portion of each of the strips of 80 molding may be cut away as at 9—10 to form a recess leading from the underside of the molding to the longitudinally extending runway and providing a way for the support which depends from the runner. The 85 runner is desirably in the form of an anti-friction device which preferably is cylindrical in form. As illustrated in Figs. 1 to 5 inclusive the cylinder is mounted axially of the longitudinally extending runway and the support is in the form of a yoke 11 having inturned ends 12 which enter suitable 90 axial apertures in the ends of the cylinder. The lower portion of the yoke 11, which desirably is a wire is bent to form an eye 14 95 adapted to receive the hook of the curtain hanger. It will be readily understood that these cylinders are adapted to slide freely in the longitudinally extending runway and that by reason of their construction they will rotate upon their axes in passing any obstruction or irregularity which may be present upon the surface of the runway. The runway may be either cylindrical, rectangular or other form, but preferably cylindrical or rectangular. If a rectangular runway is provided such as is illustrated in Fig. 5 the cylinder may be arranged transversely thereof as illustrated in Figs. 6 and 7. In such case the support for the portière 100 105 110

may be in the form of a yoke composed of two complementary brackets 17 and 18, each preferably formed of stamped metal having laterally bent yokes 19 connected by an integral cross piece 20 in which the axis 21 of the roller 6 may be journaled. The depending portions of the brackets 17 and 18 may be secured together by a rivet 21 or other suitable fastener and aligned apertures 22 provided in the lower end of said brackets to receive the hook of the curtain pin.

It is to be understood that the various forms of molding such as illustrated in Figs. 3 and 5 may be provided and that various modifications may be made in the form of the runner within the meaning and scope of the following claims.

Having thus described my invention what I claim as new and desire to secure by Letters Patent is:

- 20 1. A portière hanger comprising a member having a longitudinally extending runway, a cylindrical anti-friction runner loosely fitting therein and extending longitudinally thereof, a depending supporting member having its ends respectively connected to the ends of said cylindrical runner and having centrally depending means adapted to receive the hooks of the curtain support.
- 25 2. A portière hanger comprising a molding having a longitudinally extending runway, a plurality of loosely fitting cylindrical

anti-friction runners mounted in said runway and extending longitudinally thereof, 35 each having a depending yoke connected at its ends to said cylindrical runner axially thereof and a central eye adapted to receive the hooks of the curtain support.

3. A portière hanger comprising a molding having a longitudinal runway, a plurality of cylindrical anti-friction runners slidably mounted in said runway and extending longitudinally thereof, each supporting member including a yoke axially and rotatably secured to said cylindrical runner and having a depending eye adapted to receive the yoke of the curtain support whereby said runner is free to slide longitudinally of the runway and to rotate therein in passing 50 obstructions or roughened portions of said guideway.

4. An antifriction runner for a portière support comprising a cylindrical member adapted to slide longitudinally in a suitable 55 runway, said cylindrical member having a depending yoke connected at its ends to the ends of the cylindrical runner and having a centrally disposed eye.

In testimony whereof, I have signed my 60 name to this specification, in the presence of two subscribing witnesses.

HERBERT C. MOORE.
